UNITED STATES PATENT OFFICE

120,349

DESIGN FOR A PLATE OR SIMILAR ARTICLE

Robert A. May, Washington, Pa., assignor to
Duncan & Miller Glass Company, Washington,
Pa., a corporation of Pennsylvania

Application December 21, 1939, Serial No. 89,077

Term of patent 14 years

To all whom it may concern:

Be it known that I, Robert A. May, a citizen
of the United States, residing at Washington,
Pennsylvania, have invented a new, original, and
ornamental Design for a Plate or Similar Article,
of which the following is a specification, refer-
ence being had to the accompanying drawing,
forming part thereof.

In the drawing:

Figure 1 is a top plan view of a plate showing
my new design, and

Figure 2 is a central vertical cross-sectional
view of the plate shown in Figure 1, taken on the
line II—II of Figure 1.

The dominant feature of the design is the or-
namentation appearing on the article, and while
shown applied to a plate said ornamentation is
intended to be applied to other similar articles.

I claim:

The ornamental design for a plate or similar
article, substantially as shown and described.

ROBERT A. MAY.
